UNITED STATES PATENT OFFICE.

VINCENT T. GILCHRIST, OF SAN FRANCISCO, CALIFORNIA, ASSIGNOR TO SUPERIOR PROCESS REFINING COMPANY, OF SAN FRANCISCO, CALIFORNIA, A CORPORATION OF CALIFORNIA.

PETROLEUM-DISTILLATION PROCESS.

Application filed July 9, 1918. Serial No. 244,032.

To all whom it may concern:

Be it known that I, VINCENT T. GILCHRIST, a citizen of the United States, and a resident of the city and county of San Francisco, State of California, have made a new and useful invention, to wit: Improvements in Petroleum-Distillation Processes; and I do hereby declare the following to be a full, clear, and concise description of the same.

10 The invention relates particularly to a process for removing a high proportion of the lighter grade high gravity products, such as gasoline from crude petroleum.

Among the objects of this invention are 15 to accomplish these results without deleterious results on the quality of the tops removed or the residuum remaining, for further distillation to fuel oil or asphalt.

In this specification and the annexed 20 drawings the invention is illustrated in the form considered to be the best, but it is to be understood that the invention is not limited to such form because it may be embodied in other forms, and it is also to be understood that in and by the claims 25 following the description it is desired to cover the invention in whatever form it may be embodied.

It has been the practice heretofore to remove the "tops" from the original crude petroleum by two or more cuts and only running the first cut for the lighter gravity commodity and then combining the bottoms or residuums of the first cut top with the second cut tops, and running that for the next heaviest commodity and so on, for as many commodities as are required.

Tops may be defined as the condensate from crude naphtha first removed from crude 40 petroleum by distillation, and according to this process it is from these tops that the final volatile finished commodities are obtained by re-distillation.

My improved process of distilling gasoline or other derivatives from petroleum consists of, first removing from the crude petroleum all of the tops possible, consistent with keeping the residuum at the required gravity; and then from the total volume 50 of tops removed from the crude petroleum; to next take-off the gasoline or the lightest gravity of condensates required; to then take from the bottoms or residuums of the tops taken off the next heaviest required

condensate or commodity, this to be repeated 55 for as many times as required.

An apparatus of more or less conventional design may be used in carrying out this process, such a form being indicated in the drawings in Fig. 1, which is a diagrammatic 60 representation of a series of stills and re-fractionating columns available in the practice of this process.

Fig. 2 is a diagrammatic chart illustrating the steps and the sequence in the practice 65 of this invention.

In detail the construction illustrated in the drawings includes: The crude still 1 set within the furnace 2, heated by the burner 3. From the dome 4 of the crude still 1 the tops are carried through the pipe 5 into the bottom of the fractionating columns 6, which may be of any standard or special design, from which the vapors are carried over through the pipe 7 into the condenser 8 and 70 issue from the pipe 9 in the form of gasoline or the first final fractionation. The reflux from the fractionating column 6 drains downward through the pipe 10 into the first re-run still 11 set within the suitably heated 75 furnace 12. Any residual condensates from within the first re-run still 11, not given off from the still 11 as the desired first final fractionation pass out through the pipe 11' into the second re-run still 13 set within the 80 suitably heated furnace 14. The temperature of the furnaces 2, 12 and 14 progressively rises in the order named. Vapors from the second re-run still 13 rise through the re-fractionating column 15 and are carried over through the pipe 16 into the condenser 17 and pass therefrom through the pipe 18 as the second final fractionation.

The reflux from the re-fractionating column 15 drain back through the pipe 19 and re-enter the second re-run still 13. From the second re-run still 13 the unvaporized bottoms pass out through the pipe 20 to additional stills for further fractionation, or use as fuel distillate in accordance with the 100 extent to which it is desired to carry the process. It is usual practice to introduce pumps in the pipe 11' and 20 to maintain the desired levels in the first, second and succeeding re-run stills, each giving up its fractionation in accordance with the temperature applied. The chart shown in Fig. 2 is elucidated by the explanatory matter con-

22
fined within the brackets denoting the various steps of the process.

The re-running of the first cut tops must be done in a still equipped with an efficient 5 type of dephlegmating and refractionating column; the proportions and designs of the columns must be such as will give forth the lightest condensate cuts with a temperature difference of not less than 125° F. between 10 the temperature of the oil or tops being run and the vapor of the condensate at the condenser inlet; that is to say, the temperature between the rerun still 11 and the outlet pipe 7 in a first condenser should not be less than 15 125° F. Commodities or condensates of heavier gravity than 56 Baumé, specific gravity equal to 0.7527 to 0.7547, would require a greater temperature difference than 125° F. to distill off the maximum possible 20 volume, but the minimum allowable temperature difference has been determined for gasoline only and this description relates thereto. Subjecting the tops to a higher temperature before the lighter gravity constituents have been removed, is contrary to 25 the usual practice, and it is thought to be injurious to do so; but I have discovered and demonstrated that it is entirely practicable to subject the whole volume of tops to temperatures at least double that at which gasoline 30 would be distilled off, were the distillation made without dephlegmation, and this can be done without injury, that is without cracking either the condensates given off or 35 the residuum remaining. Another condition found to be very essential in increasing the volume of the required fractionates or condensates being removed, is to make the total volume or percentage of the first tops 40 such as will have a content of not more than 30% of the first or lightest gravity condensate or commodity to be removed. The greater the percentage or volume of the bottoms the greater will be the amount of re- 45 fractionation and separation of the desired commodity. To illustrate: If the percentage of gasoline or other desired commodity indicated by a laboratory test, either a Lebel-Henninger or similar still head is 50 about twenty percent of the original volume for which the distillation is made, it is possible to remove a volume about fifty percent greater than the laboratory indication, equal to about thirty percent of the original; while 55 if the indicated content by the laboratory method is forty percent of the original, the possible increase in volume of take off drops to about fifteen percent or about forty-six percent of the original. If the indicated 60 content by the laboratory method is as much as seventy percent of the original tops about a five percent increase in volume is all that

can be gained. Naturally if the distillation were carried to 100% basis, any method would give the same result.

I either take off all the top in one cut, or if the volume is such that two or more cuts are necessary, the several cuts would be blended into one, and the total blended volume run for the commodity of lightest gravity desired. Then rerunning the total volume of bottoms or residuum from the cut for the commodity of next heavier gravity, and so on for as many commodities as are required.

Having thus described my invention, what I claim and desire to secure by Letters Patent is:

1. The process of distilling petroleum consisting in heating the same; flowing the distilled vapor derived therefrom through a suitable refractionating column; directing said vapor into a condenser; reheating and revaporizing the reflux condensate from the refractionating column; flowing the resulting vapor back into the said column; and directing said resulting vapors into said condenser.

2. The process of distilling petroleum consisting in heating the same; flowing the distilled vapor derived therefrom through a suitable refractionating column; directing said vapor into a condenser; reheating and revaporizing the reflux condensate from the refractionating column; flowing the resulting vapor back into said column and combining the same with the first mentioned vapors and condensing said residual vapors; and passing the residuum from said refractionating column into a secondary reheating and revaporizing refractionating column.

3. A process of distilling petroleum consisting in heating the same; flowing the distilled vapor derived therefrom through a suitable refractionating column; directing said vapor into a condenser; reheating and revaporizing the reflux condensate from the refractionating column in a primary still; flowing the resulting vapor back into said column and directing said resulting vapors into said condenser; passing the residuum from said primary still into a secondary still; heating said residuum; flowing the distilled vapor derived therefrom through a secondary refractionating column; and directing said vapor into a condenser.

In testimony whereof, I have hereunto set my hand at San Francisco, California, this 2nd day of July, 1918.

VINCENT T. GILCHRIST.

In presence of:—

BALDWIN VALE,
LINCOLN V. JOHNSON.
